PROTECTIVE CUFF

Howard H. McCarl, Sheffield, Ala.

Application October 3, 1945, Serial No. 629,920

4 Claims. (Cl. 2—59)

(Granted under the act of March 3, 1883, as amended April 30, 1928; 370 O. G. 757)

1

The invention described herein, if patented, may be manufactured and used by or for the Government for governmental purposes, without the payment to me of any royalty thereon.

This invention relates to a protective cuff of the type worn by butchers, file clerks and other persons who must work in more or less public places with moist or dusty materials to protect their sleeves from being soiled by the materials handled in the course of their work.

It is an object of the invention to provide a cuff made preferably of plastic sheet material having a simple design, an effective adjustable closure and a comfortable finish at the wrist side of the cuff.

It is a further object of the invention to provide a waterproof cuff which fits comfortably around the wrist and which will protect the sleeves of the wearer from dust and stains which might be received from material handled by the wearer.

It is a further object of the invention to provide a hollow sealed bead as a protective finish for articles of wearing apparel at points where the edges of the articles come into contact with the skin of the wearer.

Further objects of the invention will be apparent from a consideration of the ensuing specification taken in connection with accompanying drawing in which:

Figure 1 is a perspective view of a pair of the cuffs as worn,

Figure 2 is a plan view of the cuff,

Figure 3 is a perspective view of the cuff as worn, and

Figure 4 is an inverted sectional view perpendicular to line 4—4 of Figure 3.

In the drawing, 10 represents a cuff formed of a single sheet of water-proof material, preferably a plastic such as vinylite. The cuff 10 is cut with curving wrist and top edges 11 and 12 and flaring sides 13 so that it fits more or less closely around the wrist of the wearer but is sufficiently large at the top to accommodate the sleeves of a shirt or coat. Reinforcing patches 14 are provided along the edges 13 and strengthen the sheet to receive a pair of fastener elements 15 and 16 on one side and two pairs of snap fastener elements 17 and 18 on the other. The snap fastener elements 18 at the elbow side of the cuff 10 are located the same distance from the outer element 17 at the wrist edge 11 of the cuff so that either of the elbow elements 18 may be engaged with the fastener 16 when the outer element 17 is secured to the corresponding ele-

2

ment 15. The four snap fastener elements 17, 18, are arranged so as to define the four corners of an oblique parallelogram, two sides of which have a length equal to the distance between spaced snap fastener elements 15 and 16; the length of the diagonal line between outer snap fastener element 17 and inner snap fastener element 18 also is equal to the distance between snap fastener elements 15 and 16 and thus equal to the length of the just-mentioned two sides of the parallelogram. This permits the side edges of the cuff to be assembled in flatly overlying relationship and the top of the cuff to be adjusted independently of the lower larger adjustment, that is, when the right-hand element 17, as seen in Figure 2, is connected to the element 15, as in Figure 3.

The material of the cuff is heavy enough ordinarily so that no special finish of the side edges 13 and top edge 12 is required. It is desirable to provide a bead 19 at the wrist edge 11 of the cuff both to insure a closer fit and to protect the wrist from chafing. In the preferred embodiment of my invention, the bead 19 is formed by turning back the wrist edge of the sheet of material forming the cuff 10 and heat-sealing the hem so formed along a line spaced from the fold. The ends 20 of the hem so formed are also closed preferably by heat-sealing, leaving a substantially rounded bead forming a sealed air pocket inside the hem. The bead 19 provides a very satisfactory finish for the wrist edge of the cuff because of its yielding quality and light weight.

A bead of this type may form a desirable finish for other articles of wearing apparel and personal use, where an edge or fold comes into rubbing contact with or bears directly on the skin of the user.

The reinforcing patches 14 may also be secured to the body of the cuff by the application of heat and pressure when a thermoplastic material is used for the cuff 10. However, it should be understood that adhesives or other means forming a tight seal may be employed with other materials as desired.

Having thus described my invention what I claim and desire to secure by Letters Patent is:

1. A protective cuff comprising a flat sheet of fluid-impermeable flexible material having a flexible limb-encircling edge, said cuff being flat in plan and closable around a portion of the body of the wearer, and said edge being finished with a hem forming a hollow flexible air-filled limb-encircling bead, said bead having its ends closed.
2. A cuff comprising a flat flexible fluid-im-

permeable sheet of material having its wrist edge folded back to form a hollow flexible limb-en-circling bead, said bead having its ends sealed to form an air pocket within the bead.

3. A closable protecting cuff comprising a flat sheet of flexible, fluid-impermeable material folded back to form a hollow flexible air-filled bead, said bead having its edges sealed to the body of the cuff along three margins, and means for adjustably closing said cuff around the wrist of 10 the wearer.

4. A closable protective cuff comprising a sheet of flexible fluid-impermeable material having tapering substantially straight side edges and adjustable closing means thereon, said closing means comprising a pair of spaced fastener elements adjacent one side edge of said cuff, and four spaced fastener elements adjacent the other side edge of said cuff, said four fastener elements being arranged so as to define the four corners of an oblique parallelogram having two sides and one diagonal of equal length corresponding to the

distance between said first-named spaced fastener elements, said first-named fastener elements being engageable with said second-named fastener elements in a plurality of positions including a diagonal position, so as to assemble said side edges of said cuff to the body of said cuff in flatly overlying relationship.
